UNITED STATES PATENT OFFICE

2,257,352

BEET HANDLING APPARATUS

Harold F. Silver, Denver, Colo.

Application February 19, 1940, Serial No. 319,678

2 Claims. (Cl. 209—104)

This invention relates to certain improvements in beet handling apparatus as originally disclosed in my pending application Serial No. 45,693, filed October 19, 1935, of which application this is a continuation in part. This is an improvement over the screening device disclosed in United States Patent No. 1,899,292 to George W. Rienks.

The present invention relates particularly to means for simultaneously conveying and screening sugar beets or the like, which commonly are mixed with dirt, leaves or other unwanted matter.

While the present invention will be described as being particularly adapted to handle sugar beets, it will be manifest that apparatus built according to this inventive concept can be used for handling other things where combined conveying and screening actions are wanted.

There is a step in the handling of sugar beets where they are elevated either for piling or for loading into a railway car, at which time dirt, leaves and other unwanted trash should be carefully separated from them and returned for reweighing in order to ascertain accurately the net weight of the beets being so elevated.

A principal object of this invention is to provide improved self-cleaning means for separating dirt, leaves and trash from sugar beets or the like, and at the same time agitate them and convey them forwardly for piling.

A further object is to provide in such a combination conveying and separating apparatus, means for collecting and returning the separated trash for reweighing.

Another object is to provide such screening apparatus that is particularly adapted to operate with an elevator, whereby the beets are delivered to said screen at a sufficient elevation above the ground so that they may be discharged from the screen by gravity.

Other objects and advantages reside in details of design and construction which will be more fully disclosed in the following description and in the drawings wherein like parts have been similarly designated and in which:

Figure 1 is a sectional view illustrating screening apparatus made according to this invention, inclusive of fragmentary sectional views of an elevator positioned to deliver beets or the like to the screen, and a fragmentary view of a conveyor positioned to carry away beets or the like from the screen;

Figure 2 is a fragmentary plan view of the apparatus illustrated in Figure 1; and

Figure 3 is a diagrammatic illustration of a typical power transmission mechanism that may well be used in operating the apparatus illustrated in Figures 1 and 2.

In order to disclose a typical embodiment of the present inventive concept, the accompanying drawings will be described in detail. However, the instant illustration is not intended to express or imply any limitation to the present invention, the scope of which is, in reality, measured by the appended claims.

In the drawings, reference character 5 denotes an elevator that is provided with an elevating belt 6 and a hugger belt 7, between which sugar beets or the like may be elevated and discharged into the separating hopper 8.

As beets are discharged from the elevator 5, they will be moving in the direction indicated by arrow 9, and they will fall upon a series of rotary screen members 10 which are rotated in the direction of the arrows 10a and which are mounted in staggered relation upon shafts 12.

Each rotary screen member 10 preferably comprises a hub 13, a plurality of radial arms 14 and a lobed rim 15 providing a non-circular perimeter. By referring to Figure 2, a preferred arrangement of these rotary screen members 10 may be visualized and it will be seen that each shaft 12 carries a plurality of the screen members, and the members on adjacent shafts 12 are in staggered overlapping relationship. The rotary screen members 10 on adjacent shafts 12 do not contact each other, but are in slight axially spaced relationship, the spacing being such that sugar beets or the like cannot fall therebetween, but dirt, leaves and trash generally will fall between the rotary screen members 10 into the lower portion of hopper 8.

Due to the non-circular contour of the perimeters of the rotary screen members 10, beets or the like discharged thereupon will be agitated as they are moved progressively forward in the direction of the arrows 10a. Obviously, this treatment tends to loosen and separate dirt, leaves and unwanted matter from the beets. Some dirt and foreign matter usually will be separated from the beets during their elevation in elevator 5 and this trash too will be delivered upon and among the screen members 10 and normally will immediately pass downwardly through the assembly of screen members into the lower portion of the hopper 8.

As the beets progress along the upper edges of the screen members 10, they will be discharged at a downward angle onto screen members 16,

carried upon shafts 12a, which rotate in a direction opposite to that of the screen members 10 as indicated by arrows 16a.

An important feature of the present arrangement is that the rotary screen members 16 that are next adjacent the rotary screen members 10 are positioned in overlapping or interlaced relationship therewith. These adjacent rotary screen members that are thus interlaced rotate in opposite directions to pull leaves, dirt and trash down into the hopper 8 and at the same time they have a definite cleaning effect on each other.

The lower rotary screen members 16 have a further cleaning effect upon the upper screen members 16 that interlace with the screen members 10. This screening effect may be still further enhanced by driving the two shafts 12a at slightly different speeds, which is the preferred arrangement.

While this arrangement is particularly efficient in pulling leaves, trash and dirt away from the beets and down into the hopper 8, it does not tend to drag the beets through but rather carries or bounces them along on the surfaces of the screen members as they are conveyed forward.

As the beets traverse the upper edges of the screen members 16, they will be moving in a direction opposite to said upper edges, but the forward and downward components of motion imparted to them by the rotary screen members 10 and by gravity will move them along into discharge spout 17, but dirt, leaves and trash generally, of lighter weight, that may still be present, will tend to be thrown back and into the lower portion of hopper 8.

The screened beets thus separated from their accompanying dirt and trash will be delivered to a conveyor belt 18, to be taken to the storage pile or the railway car.

Dirt, leaves and trash will fall through the open bottom 8a of the hopper 8 to be discharged onto a conveyor 19, to be taken to a suitable collecting receptacle for reweighing in order accurately to determine the net weight of the beets being handled.

The diagrammatic illustration that is Figure 3 depicts typical power transmission mechanism for driving the various components hereinbefore described.

Reference character 20 is a sprocket chain for transmitting driving power from a prime mover, not shown, to a driven sprocket 21 which drives a gear 22 meshing with a driven gear 23, which in turn drives the hugger belt 7 of the elevator 5. A sprocket chain 24 drives a sprocket 25 to actuate the elevator belt 6.

A sprocket chain 26 drives a sprocket 27 mounted upon the first shaft 12 of the series, and driving power is thence transmitted through the intermediary of a series of short sprocket chains 28 to rotate each of the shafts 12 and their associated rotary screen members 10 in the direction indicated by the arrows 10a.

The last shaft 12 in the series carries a gear 29 that meshes with a similar gear 30 carried upon the first shaft 12a, which is thereby rotated in the opposite direction. A short sprocket chain 31 transmits power to the other shaft 12a so that these shafts 12a and their associated rotary screen members 16 will rotate in a direction opposite to that of the screen members 10.

Radial projections 33 may be provided at the perimeters of the rotary screen members 16, the

purpose of which is further to facilitate the self-cleaning function thereof.

The slight differential in the speed of rotation of the two shafts 12a which carry the rotary screen members 16, brings the projections 33 around between the opposite pairs of screen members at a different relative position at each rotation. The continuous closed rims of the rotary screen members 10 and 16 are advantageous in their cleaning, screening, agitating and conveying functions, particularly in those adjacent members that rotate in opposite directions, but this continuous closed rim 15 may be omitted from some of the members 10. Solid rolls in place of the rotary screen members 16 are not self-cleaning nor as efficient in their screening functions, because they cannot be interlaced with each other nor can they be interlaced with the next adjacent rotary screen members 10. Under some circumstances, the lower shaft 12a and its associated rotary screen members 16 may be omitted, leaving only the shaft 12a and the screen members 16 that are next adjacent to and interlaced with some of the screen members 10.

Thus the stated and other inferred objects and advantages of this invention are fully effected and while this specification discloses a preferred embodiment of this inventive concept, changes as desired may be made within the scope of the appended claims without departing from this inventive concept.

What I claim and desire to secure by Letters Patent is:

1. In apparatus of the character disclosed, the improvement which comprises a plurality of shafts mounted for rotation in a substantially horizontal plane, a plurality of axially spaced lobed screen members mounted on said shafts in staggered interlaced positions with reference to each other, a plurality of shafts journaled below the plane of the first said shafts in a plane that is inclined with reference to the plane of the first said shafts, a plurality of axially spaced lobed screen members mounted upon the last named shafts in staggered interlaced relationship with each other, the rotary screen members on the shaft in the horizontal plane and the next adjacent shaft in the inclined plane being also in staggered interlaced relationship with each other, and means for rotating the shafts in the horizontal plane and the shafts in the inclined plane simultaneously and in opposite directions.

2. In apparatus of the character disclosed, the improvement which comprises a plurality of shafts mounted for rotation in a substantially horizontal plane, a plurality of axially spaced lobed screen members mounted on said shafts in staggered interlaced positions with reference to each other, a plurality of shafts journaled below the plane of the first said shafts in a plane that is inclined with reference to the plane of the first said shafts, a plurality of axially spaced lobed screen members mounted upon the last named shafts in staggered interlaced relationship with each other, the rotary screen members on the shaft in the horizontal plane and the next adjacent shaft in the inclined plane being also in staggered interlaced relationship with each other, and means for rotating the shafts in the horizontal plane and the shafts in the inclined plane simultaneously and in opposite directions and at different speeds of rotation.

HAROLD F. SILVER.
